4 Claims. (Cl. 141—135)

This invention relates to a machine for forming, filling and closing flexible walled bags and, more particularly, to a machine in which the bags are formed by heat sealing two strips of packaging material transversely to form a series of connected bags and in which the bags are severed and advanced by a carrier through closing and filling stations.

The general object of the invention is to provide in a machine of the above character a novel filling mechanism which permits the bags to be advanced with a continuous motion and at a high rate of speed and which, at the same time, accurately fills the bags.

Another object is to fill the bags by means of continuously moving spouts which advance with the bags and deposit a product to be packaged in the bags rapidly and with a minimum of dusting.

Other objects and advantages of the invention will become apparent from the following detailed description taken in connection with the accompanying drawings, in which

FIGURE 1 is a perspective view of a packaging machine embodying the novel features of the present invention.

FIG. 2 is an enlarged perspective view of a package made on the machine.

FIG. 3 is a schematic perspective view illustrating the steps performed on the machine.

FIG. 3a is a schematic perspective view forming a continuation of the right-hand side of FIG. 3.

FIG. 4 is a schematic view illustrating the drive to the various mechanisms.

FIG. 4a is a schematic view forming a continuation of the right-hand side of FIG. 4.

FIG. 5 is a fragmentary front elevational view of the filling mechanism, parts being broken away and shown in section.

FIG. 6 is an enlarged fragmentary sectional view taken along the line 6—6 in FIG. 1.

FIG. 7 is an enlarged fragmentary plan view of the filling mechanism, parts being broken away and shown in section.

As shown in the drawings for purposes of illustration, the invention is embodied in a machine for forming, filling and closing a pouch or bag 30 which is composed of two rectangular panels 31 disposed face to face and joined together at their margins preferably by a fold at the bottom and heat seals 32 and 33 at the top and sides respectively. Herein, the bags are made from a web 34 of sheet material either composed of or coated on one side with a thermoplastic material and drawn off a supply roll 35. The web is folded longitudinally (see FIGS. 3 and 3a) and the two resulting strips 34a are heat sealed together transversely at spaced intervals as indicated at 36 to form a series of connected bags. The latter then are separated by cutting the seals 36 intermediate their edges so that each seal forms the trailing side seal 33 of one bag and the leading side seal of the next bag. After being separated from the web 34, each bag is filled with the product to be packaged and then is closed by the top seal 32.

The various mechanisms for advancing, folding and cutting the web 34 and for advancing, filling and closing the bags 30 are mounted on an elongated, horizontal base

2

37 and are operated in timed relation to each other by a horizontal shaft 38 (FIGS. 4 and 4a) journaled in and extending lengthwise of the base. The supply roll 35 is supported on the end of the machine base 37 by a bracket 39 and the web 34 is drawn off the roll and over a plow 40 which is located at a station 41 and which folds the web longitudinally, the web being advanced in this case by two sets of feed rollers 42 and 43 spaced along the base (FIGS. 1 and 4). From the folding station, the web is advanced to a station 44 where the cross seals 36 are formed and then to a cut-off station 45 where the successive end bags are severed from the web. After being cut from the web, the bags are carried edgewise by a conveyor 46 (FIGS. 1 and 5) which carries the bags first through a filling station 47 and then through a top sealing station 48. As shown in FIG. 5, the conveyor forms an extension of the path of the web 34 and the bags are supported in spaced relation on the conveyor by grippers or clamps 50 and 50'.

The various mechanisms for forming, filling and closing the bags 30 are constructed and correlated with each other in a novel manner so that the web 34 and the bags on the conveyor 46 may move continuously and at a comparatively high speed to produce a large number of completed packages per minute while maintaining the accuracy of the fill and the overall neatness of the packages. To these ends, the mechanisms are constructed so that they may perform their individual functions in periods larger than in prior machines of this type and yet still produce packages at a higher rate.

In general, the high rate of production is achieved while the accuracy and neatness of the package is maintained by arranging the operating mechanisms to move with the web 34 and the bags 30 as they are performing their packaging functions but to operate with the same precision and ruggedness as the corresponding mechanisms of appreciably slower machines heretofore employed. Thus, the mechanism 51 for forming the cross seals 36 firmly engages the web without stretching or wrinkling the latter to make strong, neat and accurately spaced seals. Similarly, the bags are positively held open preparatory to filling, the air in the bag is displaced first by the filling mechanism 52 rather than by the product and the bags are filled from the bottom, all this being accomplished over a comparatively long period in spite of the high speed production of the machine. Also, the top seals 32, like the side seals 33, are made precisely to maintain the attractive appearance of the bag.

In the present instance, the shaft 38 (FIGS. 4 and 4a) for driving the operating mechanisms is journaled in bearings 53 and is rotated continuously by a motor 54 through speed reducing chain drive 55. Both sets of feed rolls 42 and 43 are driven in unison from a common shaft 56 which is journaled on the base 37 parallel to the drive shaft 38 and driven, in turn, by the latter through a chain 57, and intermediate shaft 58 and a chain 59. The feed rolls 42 are rotatably supported on opposite sides of the web 34 by a bracket 60 (FIG. 1) which is mounted on the base 37 in advance of the sealing station 44. Meshing gears 61 (FIG. 4) fast on the rolls drive the latter together but in opposite directions and are driven from the shaft 56 through bevel gears 62. Similarly, the feed rolls 43, which are journaled in a bracket 63 on the opposite side of the sealing station, are driven from the shaft 56 through bevel gears 64 and meshing gears 65 on the lower ends of the rolls. One roll of the set 43 has a rubber covering 66 which stops short of the fold line of the web and prevents excessive creasing. The rolls 42 and 43 draw the web 34 from the supply roll 35 and across the plow 40 which may be of well-known construction and comprises a stationary triangular plate 67 supported on the

base 37 and inclined downwardly, the web being folded around the plate by upright idler rollers 68.

In order that the operating parts of the sealing mechanism 51 may move with the web 34 to provide a sufficient period for heat sealing the web and still form neat seals 36 without stretching or wrinkling, this mechanism includes two units 69 and 70 each of which carries a plurality of sealing bars 71 (see FIGS. 4 and 4a) opposing the bars on the other unit and the two units are given an orbital movement. Thus, the units move together and into engagement with opposite sides of the web and then move along with the web at the same speed at which the latter is advancing. During the period in which the sealing units 69 and 70 are traveling with the web, the bars 71 form a plurality of cross seals 36 and then the units are backed away from the web. The orbital path is completed by the units moving back in a direction opposite to the web advance. In this way, the bars 71 may be supported firmly on the units against twisting and yet may be individually yieldable to produce the optimum pressure for making the seals 36.

To give each of the sealing units 69 and 70 the desired orbital motion, each unit is supported on elongated horizontal bars 100 and moved by endless chains disposed above and below the unit. Thus, as shown in FIGS. 3 and 4, the front sealing unit 69 is connected to a pair of endless chains 72 above the unit and a similar pair of chains 72' below. In the same manner an upper pair of chains 73 and a lower pair 73' support the rear sealing unit 70, the construction for the two units being substantially the same. Thus, the upper chains 73 are disposed end to end and the adjacent ends are driven by sprocket wheels 74 (FIG. 4) whose shafts 75 are journaled in a horizontal stationary plate 76 (FIG. 1). The similar pair of chains 72 supporting the upper end of the front sealing unit 69 are driven by sprocket wheels 86 fast on shafts 87 (FIG. 4).

All of the chains for both sealing units 69 and 70 are driven in unison from the drive shaft 58 through bevel gears 88 (FIG. 4) and an upright shaft 89, and a gear 93 keyed to the upper end of the shaft 89 drives a gear 94 meshing with one of the gears 95 on the rear sprocket wheel shafts 75. A gear 96 meshing with both of the gears 95 completes the drive to these two shafts and also drives the front chains 72 through an idler gear 97 and gears 98 on the front sprocket wheel shafts 86. A similar gear train drives the lower chains as indicated by the primed reference characters in FIG. 4.

To provide heat for the sealing mechanism, power from a suitable source is connected through rheostats 119 (FIG. 1) in a control panel 120 and then to a signal box 121 mounted on the plate 76. From the box, flexible leads 122 extend to the ends of each sealing unit 69 and 70 and then through a conduit 123 to heating coils (not shown) in the seal bars 71. The motor 54 is controlled through well-known circuitry by a switch 138 (FIG. 4) actuated by a cam 139 on the drive shaft 38.

When the cross seals 36 have been made to form a series of connected bags, the latter are advanced by the feed rolls 43 to the cut-off station 45 where the terminal bag is severed from the strip. The cutting is effected by knife units 140 and 141 disposed on opposite sides of the web and operable to cut the web transversely intermediate the edges of each seal 36. As shown in FIGS. 3 and 4, the knife units 140 and 141 comprise upright drums 142 and 143 journaled on the base 37 by means of shafts 144 and 145 (FIG. 4) to turn about their longitudinal axes. The drums are turned continuously from the drive shaft 58 and carry cutter elements which cooperate with each other to sever the end bag.

To drive the drums 142 and 143, a vertical shaft 156 (FIG. 4) is journaled on the base 37 and is driven from the drive shaft 58 through bevel gearing 157. A gear 159 keyed to the upper end of the shaft 156 meshes with an idler gear 160 which, in turn, meshes with a gear 161 on

the lower end of shaft 144 of the drum 142. A second gear 162 keyed to this shaft meshes with a gear 163 equal in size and keyed to the shaft 145 of the drum 143 so that the two drums are turned in unison but in opposite directions.

Although the bags 30 are edge-to-edge when attached to the web 34, they are spaced apart when carried by the conveyor 46 so as to permit more accurate and neater filling and closing operations. To effect such spacing, the conveyor is driven at a faster speed than the web. For example, the linear speed of the web may be about 16 inches per second while the conveyor may move at a speed of approximately 22 inches per second. In order that each bag 30 as it is cut from the web is delivered to a clamp 50 (FIG. 5) on the conveyor, it is accelerated and momentarily moves at a speed faster than the conveyor.

To transfer the severed bag 30 from the web 34 to the conveyor 46 and, at the same time, to speed up the rate of travel of the bag, an accelerating mechanism 164 (FIG. 3) is disposed between the cut-off station 45 and the adjacent end of the conveyor. The accelerator 164 includes a first pair of vertical rollers 165 and 166 (FIG. 3) which receive the leading edge of the end bag on the web just before this bag is cut by the knife units 140 and 141. The timing is such that the rollers 165 and 166, which are turning at a higher peripheral speed than the web advance, slip momentarily as the bag is cut. These rollers then accelerate the bag and deliver it between a second pair of rollers 167 and 168 which are turning at the same speed as the first pair and the second pair of rollers, in turn, delivers the leading edge of the bag to one of the clamps 50 on the conveyor 46. Since the peripheral speed of the rollers 167 and 168 is greater than the linear speed of the conveyor and since the clamp is closed before the bag is released by these rollers, the bag will buckle slightly during the transfer. Such buckling insures that the bag is inserted completely in the clamp and properly positioned for subsequent operations. Preferably, a second complete set of rollers are disposed below the rollers 165, 166, 167 and 168 so that the bag is engaged at vertically spaced points and kept upright.

Herein, the conveyor 46 comprises an endless chain 194 (FIG. 4a) disposed in a horizontal plane with a straight run extending from a point adjacent the accelerator 164 through the filling and closing stations 47 and 48. At its forward end, the chain drives the accelerator through a suitable sprocket connection (not shown). The other end of chain extends around a sprocket wheel 197 (FIG. 4a) keyed to the upper end of a vertical shaft 199 which is journaled on the base 37 and driven by the shaft 38 through bevel gears 199. For the sake of rigidity, a second chain 194' also is employed and is disposed below the chain 194 to extend around a sprocket wheel 197' on the shaft 198.

The normal spacing between a leading clamp 50 and a trailing clamp 50' corresponds to the width of a bag but, as the leading edge of a bag is being gripped by the clamp 50, the other clamp is turning about the center of the sprocket wheel (not shown) at the leading end of the conveyor and therefore it trails the clamp 50 by more than a bag width. As the clamp 50' comes off the sprocket wheel, it catches up with the trailing edge of the bag and grips this edge. After gripping the bag, the clamp 50' is rocked forward to move the bag edges together and separate the panels 31 preparatory to filling, and the bags are thereafter held open until they have been filled.

After the bags 30 have been severed from the web 34 and picked up by the conveyor 46, the latter advances the bags through the filling station 47 where the dispensing mechanism 52 deposits a measured amount of product 250 in each bag in a new and improved manner. The novel dispensing mechanism includes a plurality of clamshell buckets 251 which move continuously along an endless path a portion of which coincides with the path of

the bags on the conveyor. While the buckets 251 are away from the path of the bags, they receive the product from a measuring device 252 and then, when the buckets are over the bags, one is inserted in each bag. Thereafter, the bucket moves at the same speed as the conveyor. The bucket is not opened until it reaches down substantially to the bottom of the bag so that the bucket displaces the air in the bag before the product is deposited and this provides a quick fill which does not produce dusting when the product is a powder.

As shown in FIGS. 5 and 7, the buckets 251 are spaced along an endless chain 253 which has a run 254 extending over a portion of the conveyor 46, this being the run where the buckets are lowered into the bags. From the end of this run the chain extends rearwardly and then reversely around sprocket wheels 255 and 256 where it enters a curved run 257. As the buckets move along the curved run, they receive the product from the measuring device 252 which is in the form of a turret whose radius coincides with the radius of the curved run. From the latter, the chain 253 extends around an idler sprocket wheel 258 and back to the straight run 254. Preferably, two chains 253 and 253' are employed and follow identical paths in vertically spaced planes.

The chains 253 and 253' are positively guided along the straight run 254 and the curved run 257. For this purpose, the rollers of the upper chain 253 ride in a guide 259 along the straight run and in a guide 260 along the curved run while similar guides 259' and 260' receive the rollers of the lower chain 253'. The lower guides are fastened to a horizontal plate 261 on opposite sides of a vertical spacer plate 262 which supports a second horizontal plate 263 to which the upper guides are secured. The three plates 261, 262 and 263 are bolted together to form a rigid supporting structure 264 which is fixed to the base of the machine. Each of the guides 259 and 259' is formed by two straight bars 265 and 266 having in-turned flanges which define a track for the chain rollers while curved bars 267 and 268 with flanges form the track for the curved run 257.

The chains 253 and 253' are driven from the drive shaft 38 through a chain drive 269 (FIG. 4a), bevel gears 270 and an upright shaft 271 journaled on the base 31. Through a gear train 272 disposed in a gear box 273 on the plate 263, the shaft 271 drives a shaft 274 which extends vertically between the plates 261 and 263 and is journaled on the support 264 at the end of the straight run 254, the sprocket wheels 255 being fast on the shaft 274. The sprocket wheels 256 are journaled in the opposite ends of a vertical post 275 which is fastened to the outer ends of arms 276 mounted to turn about an axis *a* to tension the chains, the arms then being locked in position by a clamp 277. The third pair of sprocket wheels 258 are journaled in the ends of a post 278 which is carried by the forward end of the support 264.

To carry the buckets 251 on the chains 253 and 253' while supporting them for raising and lowering, vertical guides 279 span and are connected to the chains. As shown in FIGS. 5 and 6, each guide is composed of two vertical channel members 280 spaced apart and facing each other. At their ends, the channels are fixed to blocks 281 which are fastened to the links of the chains 253 and 254'. A slide 282 is disposed between and projects into each pair of channels to slide up and down and a bracket 283 projecting outwardly from the slide support a bucket 251. The vertical movement of the slides 282 and hence of the buckets 251 is under the control of rollers 284 journaled on the backs of the slides and riding in tracks 285 and 286 extending along both sides of the plate 262. The track 285 is formed by parallel bars 287 set out from the plate 262 by spacers 288 and suitably fastened to the plate. The track 286 is similarly formed by curved bars 289 and spacers 290.

Herein, each of the buckets 251 is composed of two shells 291 and 292 which are U-shaped in cross section

and face each other with the flanges of one overlapping the flanges of the other and with the two shells tapering downwardly to a point. The inner shell 292 is stationary and is riveted to the back of the bracket 283 while the outer shell 291 is pivotally supported by pins 293 on the spaced arms 294 of the bracket. The bucket is held closed by a U-shaped spring 295 whose ends are secured to the bracket arms 294 and which bears against the movable outer shell 291. The latter is swung open by a roller 296 carried on one end of an arm 297, the other end being secured to the top of the shell 291. After the bucket has been lowered into a bag 30, the roller 296 rides under a cam bar 298 which is secured to the plate 262 and which depresses the roller 296 relative to the slide 282 to swing the shell 191 out against the action of the spring 295.

As shown in FIG. 6, the product 250 to be packaged, which may be a free flowing powder, is delivered from a suitable source (not shown) to a hopper 299 through an opening 300 in one side thereof. The hopper is secured to and extends around a part of an upright tube 301 which is secured to the base 37 and which provides a support for the plate 261 and, through a bracket 302, supports the plate 263. The product flows by gravity from the hopper 299 through an opening 303 and into the lower end of the tube 301 and the product is raised in the tube by an auger 304 driven by a motor 305 (FIG. 1). At the top of the tube, the product flows out through a lateral opening 306 (FIG. 7) and onto a chute 307 from which it falls into a measuring bucket 308, the overflow returning it to the hopper 299.

The measuring buckets 308 are spaced around a turret 309 which turns about the axis of the tube 301. For this purpose, the turret includes a sleeve 310 which is rotatably supported on the tube by an air bearing formed by a collar 311 fixed to the tube and having a flange 312 projecting out under a sleeve 310. Compressed air from a suitable source (not shown) is supplied through a hole 313 connected to a bore 314 in the flange 312. The bore 314 communicates with an annular passage 315 which is formed in the collar 311 and opens outwardly through ports 316 in the collar. Thus, the sleeve 310 turns on a cushion of air. Rotation of the turret 309 is effected by the chain 253 and, to this end, a plurality of arms 317 radiate from the sleeve 310 and are provided on their outer ends with sprocket teeth 318 which project into spaces between the blocks 281. Thus, the turret is turned in synchronism with and at the same speed as the chains 253 and 253'. There is one chute 307 for each bucket 308 and the chutes are supported on the sleeve 310 by brackets 319 to turn with the buckets.

The measuring buckets 308 are filled on the back side of the turret 309 and then the product is leveled in the buckets by an arm 320 (FIG. 7) secured to the inside of a housing 321 which encloses the measuring device 252. The arm 320 is substantially even with the tops of the buckets 308 and brushes the excess product off the buckets and back into the hopper 299. After being leveled, the measuring buckets 308 enter a path above the curved run 257 of the chains 253 and 253' and, at this time, a measuring bucket is disposed over each filling bucket 251 on the curved run 257 and the two sets of buckets are traveling at the same speed. When thus aligned, the measuring bucket is opened and the product falls into the filling bucket.

Each of the measuring buckets 308 comprises a tapered shell 322 which is U-shape in cross section and rigidly secured to a bracket 323 projecting radially from the sleeve 310. The open inner side of the shell 322 is closed by a flat plate 324 carried on the lower end of a generally upright lever 325. The latter is fulcrumed intermediate its ends on the sleeve 310 to turn about a horizontal axis and is biased in a direction to hold the plate 324 in the closed position by a torsion spring 326. When the measuring bucket 308 is traveling above a filling bucket 251,

the lever 325 is rocked to swing the plate 324 to the open position and transfer the product to the filling bucket. For this purpose, a roller 327 is journaled on the upper end of the lever and engages a stationary cam 328 which is disposed adjacent the curved run 257 and supported by the collar 312. When the product is transferred to the filling bucket 251, the latter advances around the sprocket 258 to the straight run 254 where it deposits the product in a bag.

After the bags 30 have been filled at the station 47, the conveyor 46 advances the bags to the closing station 48. At the station 48, the top seals 32 are made by a sealing mechanism 330 (FIGS. 1 and 3) which is generally similar to the cross sealing mechanism 51.

The sealing units 69" and 70" (FIG. 4a) are generally similar to the upper halves of the sealing units 69 and 70 and the corresponding parts are indicated by the same but double primed reference characters. Thus, the unit 69" is mounted on a pair of chains 72", only one of which is shown in FIG. 4a, and includes an elongated horizontal bar 100" suitably supported on the chains and carrying the horizontally disposed sealing bars (not shown). The sealing unit 70" is similarly constructed and is supported by a pair of chains 73". The chains 72" and 73" are driven by sprocket wheels 74" and 86" respectively and these, in turn, are driven from the shaft 38 through a chain drive 331, bevel gears 332 and a vertical shaft 333 journaled on the base 37. The gear drive from the vertical shaft is substantially the same as for the chains 72 and 73 as indicated by the corresponding reference characters but includes an additional idler gear 334. Flexible leads 122" (FIG. 1) connect the heating elements in the horizontal seal bars to rheostats 340 in the control panel 120.

The formation of the top seals 32 at the station 44 completes the bags 30 which are then removed from the end of the conveyor 46 by an oscillating arm 341 (FIG. 4a). The arm is horizontally disposed to project in behind the end bag on the conveyor 46 and is pivotally supported on a horizontal crank 342. The latter is rotated by the shaft 38 through a chain drive 343 and bevel gears 344 to swing the arm 341 rearwardly in timed relation with the advance of bags to kick each end bag from the machine. Continued rotation of the crank 342 withdraws the arm 341 from the path of the bags after each bag has been removed and then projects the arm in behind the next bag.

We claim as our invention:

1. In a machine for filling bags having open upper ends, the combination of, a frame, a first carrier on said frame operable to support a succession of equally spaced bags and advance the same open end up along a predetermined path through a filling station with a continuous motion, a second carrier on said frame having a run extending over said path, mechanism for driving said second carrier continuously at the same speed as said first carrier, a plurality of spouts equally spaced along said second carrier and each disposed above one of said bags along said run, each of said spouts comprising a pair of shells pivotally connected together to swing toward and away from each other about an axis paralleling said run and spaced from the lower ends of the shells thereby to close and open the lower end of the spout, a spring urging the shells of each spout together and normally closing the spout, means mounting said spouts on said second carrier for up and down movement between elevated positions above the level of the bags and lowered positions in which the lower ends of said spouts are inserted in the bags, means on said frame for moving said spouts into said lowered positions

and into the bags as the spouts approach said filling station, a follower fast on one shell of each spout and operable when moved in one direction to open the spout, and a cam fast on said frame and positioned to engage said followers and open successive spouts when the latter are in said filling station.

2. The combination defined in claim 1 in which one of said shells is fast on said second carrier and said follower is fast on the other of said shells adjacent the upper end of the latter to swing the lower end of said other shell away from said one shell as said follower is moved in said one direction.

3. In a machine for filling bags having open upper ends, the combination of, a first carrier operable to support a succession of equally spaced bags and advance the same open end up along a predetermined path to and through a filling station with a continuous motion, a second carrier having a run extending over said path, mechanism for driving said second carrier continuously at the same speed as said first carrier, a plurality of normally closed spouts equally spaced along said second carrier and each disposed above one of the bags along said run, means for delivering measured charges of a product to said spouts while the latter are closed, means mounting said spouts on said second carrier for up and down movement between elevated positions above the level of the bags and lowered positions in which the lower ends of the spouts are inserted in and adjacent the bottoms of the bags at the filling station, means on said machine for moving successive spouts into said lowered position as the spouts approach said filling station, and mechanism for opening the lower ends of said spouts when the latter reach the filling station thereby to deposit said charges in said bags.

4. In a machine for filling bags having open upper ends, the combination of, a frame, a first carrier on said frame operable to support a succession of equally spaced bags and advance the same open end up along a predetermined path to and through a filling station with a continuous motion, a second carrier on said frame having a run extending over said path, mechanism for driving said second carrier continuously at the same speed as said first carrier, a plurality of spouts equally spaced along said second carrier and each disposed above one of said bags along said run, each of said spouts comprising a pair of shells pivotally connected together to swing toward and away from each other about an axis paralleling said run and spaced from the lower ends of the shells thereby to close and open the lower end of the spout, a spring urging the shells of each spout together and normally closing the spout, means mounting said spouts on said second carrier for up and down movement between elevated positions above the level of the bags and lowered positions in which the lower ends of said spouts are inserted in and adjacent the bottoms of the bags at said filling station, means on said frame for moving said spouts into said lowered positions and into the bags as the spouts approach said filling station, and means for opening for swinging the lower end portions of said shells apart and opening successive spouts when the latter are in said filling station.
